US0D1006919S

(12) **United States Design Patent** (10) **Patent No.:** **US D1,006,919 S**
(45) **Date of Patent:** **** Dec. 5, 2023**

(54) **SPORTS EQUIPMENT**

(71) Applicant: **Qidu Electronic Commerce (Zhejiang) Co., Ltd.**, Ningbo (CN)

(72) Inventor: **Linying Xie**, Ningbo (CN)

(73) Assignee: **Qidu Electronic Commerce (Zhejiang) Co., Ltd.**, Ningbo (CN)

(**) Term: **15 Years**

(21) Appl. No.: **29/831,708**

(22) Filed: **Mar. 22, 2022**

(51) LOC (14) Cl. **21-02**

(52) U.S. Cl.

USPC **D21/680**

(58) **Field of Classification Search**
